UNITED STATES PATENT OFFICE.

WILLIAM P. HOMANS, OF CANTON, MASSACHUSETTS, ASSIGNOR TO ALSATIAN MACHINE WORKS, LIMITED, OF BOSTON, MASSACHUSETTS, A CORPORATION OF MASSACHUSETTS.

BEARING FOR TOP-DETACHING ROLLS.

Application filed June 8, 1926. Serial No. 114,535.

My improvement relates more particularly to the class of detaching rolls described in Letters Patent of the United States, No. 1,546,763, granted to H. Tunstall

5 July 21, 1925.

Heretofore top detaching rolls such as are described in said patent have rotated at each end within a bushing or sleeve the outer surface of each of which has been of 10 more than one diameter or otherwise of such shape as to form a shoulder or shoulders. The bearings which hold the top roll down rest on the portions of smaller diameter and the bearings rest against the shoulders 15 which prevent endwise movement of the rolls. Sometimes, however, if the rolls and bearings are not properly adjusted in the fixing of the machine, the bearings are caused to rest on the shoulder or periphery 20 of the larger part of the bushing instead of on the smaller diameter thereof, so that the shoulder does not bear against the bearing and so that the bearing does not rest firmly on the bushing thereby permitting the 25 roll to move endwise out of its proper place or the bushing to escape from the insecure grip of the bearing or the roll or bushing or both to drop down into the machine and hence prevent its proper working.

30 As shown in said patent, the bearings are mounted on springs 94 or, as is quite usual on a weighted lever which is given a proper detaching movement, preferably about the axis of roll 87 as in that patent.

35 My improvement is intended to overcome these troubles, and it consists, generally speaking, in eliminating the shoulders and in providing means other than the shoulders for holding the top roll from moving end-

40 wise. Thus instead of reducing the diameter of a portion of the bushing to form a shoulder, I provide a bushing or sleeve of proper uniform outside diameter and of suitable length and properly shaped on its

45 interior to fit on each end of the roll, within which the roll may rotate and upon which the bearing will rest. Thus it is more or less immaterial exactly where the bearing strikes the bushing. The shoulder having

50 been eliminated by this construction, I have provided a stop wall at each end of each roll so that the roll may butt against it and the roll will have no possibility of any sub-

stantial endwise play, and I also close the space at the side of the lower roll so that 55 the top roll may not fall through into the machine, all as described below.

My invention will be understood by reference to the drawings where it is shown in its preferred form.

Figure 1 is a plan of a top roll mounting, showing only the forks 14, while attached to the lever 140 as shown in Fig. 2.

Fig. 2 is a cross section taken through the rolls of Fig. 1, showing means for supporting both the top and bottom rolls and omitting any detail of the bottom rolls.

1 is a portion of the frame of the machine which supports a casting 2 within which the bottom rolls 4 are supported. 70 The casting 2 has mounted upon it a plate 5 which is bolted thereto by bolts and nuts 6, and is not further described as it forms no part of my invention. It is also provided with recesses 7 between the portions 11 in

75 which lie the front top rolls 8 which rest on the bottom rolls 4 (see Fig. 2). It is provided also with arms 9 which have lateral extensions 10 running parallel with the axis of the top roll, the side wall 120 of which 80 comes close enough to the corresponding bottom roll to prevent the top roll from falling down into the mechanism below it, if in setting, it should not be held by the bearing.

See Fig. 2 where it will be noted that the 85 space between the lower edge of the part 120 and the lower roll 4 is not sufficient to allow the roll 8 to fall down into the machine. It will be understood that there

are a series of these detaching rolls extending the length of the machine and located in usual relation to the several nipper frames. Sleeves or bushings 12 fit onto the ends of each top detaching roll so that

85 the rolls may turn therein, these sleeves 90 being of somewhat large peripheral diameter, approximately that of the diameter of the body of the detaching roll, and it will be noted from Fig. 1 that these sleeves are engaged by the forks 14 on the

95 end of the levers 140 which corresponds with the spring 95 in said patent. The ends of the detaching rolls themselves abut

100 against the surface 13 of the casting 2 so that they can have no endwise motion. They are, 105 however, preferably given an oscillating

motion as described in the said patent, about the lower roll, because they lie in the bearing forks 14 of the arms 140 (see Fig. 2), these arms 140 being given a swing like the arm 97 of the said patent in any desired way. This bearing 14, however, because of the construction of the sleeve 12 which is of uniform diameter throughout, may bear upon any portion of the sleeve 10 without in any way disarranging the operation of the machine, and as the ends of the top roll abut the side wall 13 of the casting, the top roll will be held in place without any shoulder, as above described.

15 The front top roll although shown in the bearings is not particularly described as it may be of any usual construction and mounted in any usual way. As shown, it has bushings 12 corresponding with the 20 bushings on the top rolls.

It will be seen that the top detaching roll in each case turns freely in its sleeve or bushing and is held against its bottom roll by its bearing, the bottom rolls being 25 mounted to turn in the casting 2 as usual.

The interior of the bushings or sleeves 12 is suitably shaped to fit approximately the ends of the rolls so that the ends of the rolls may turn freely in them, and the 30 spaces between the opposing surfaces of two adjacent castings is such as to allow the rolls no substantially end play without preventing their free rotation in their bushing.

What I claim as my invention is:—

1. In a machine of the kind described, 35 having top rolls and bottom rolls, a top roll having at each end a bushing of substantially an equal diameter throughout and a socketed interior to receive an end of said top roll, and bearings to hold said top roll 40 in proper relation to a bottom roll adapted to engage a bushing at any portion of its periphery.

2. In a machine of the kind described, having top rolls and bottom rolls, and castings spaced apart to form an opening to receive said rolls, a top roll having bushings 45 freely supported thereon at each end, the opposing surfaces forming the ends of said opening being adapted to engage the ends 50 of said bushings and prevent the endwise motion of said top roll.

3. In a machine of the kind described comprising a frame and top rolls and bottom rolls, said top rolls having bushings 55 freely supported on their ends, said frame comprising means to support said bottom rolls and walls opposite to each other and having extensions at right angles to said walls, the whole forming recesses to receive 60 the bushings of said top rolls, said extensions being spaced from the adjacent bottom roll a distance less than the diameter of said top roll, whereby said top roll if loose cannot pass by said bottom roll.

WILLIAM P. HOMANS.
